UNITED STATES PATENT OFFICE.

WILLIAM H. CLOUD, OF KOKOMO, INDIANA, ASSIGNOR OF ONE-HALF TO
WILLIAM STYER, OF SAME PLACE.

PUMP.

SPECIFICATION forming part of Letters Patent No. 396,193, dated January 15, 1889.

Application filed March 15, 1888. Serial No. 267,212. (No model.)

To all whom it may concern:

Be it known that I, WILLIAM H. CLOUD, a citizen of the United States, residing at Kokomo, in the county of Howard and State of Indiana, have invented a new and useful Improvement in Pumps, of which the following is a specification.

My invention relates to an improved pump for raising water from wells and cisterns.

10 The objects of my improvement are, first, to provide improved means for connecting the upper and lower sections of the pump-stock, and, second, to provide improved means for draining the upper section, all as hereinafter 15 fully described.

The accompanying drawings illustrate my invention.

Figure 1 represents a vertical section of the pump-stock and pump-staff. Fig. 2 represents 20 a side elevation of the pump. Fig. 3 is a perspective view, on an enlarged scale, of the coupling for connecting the upper and lower sections of the pump-stock. Fig. 4 represents a side elevation of the pump-cylinder. 25 Fig. 5 represents a central longitudinal section of the same.

The upper section, A, of the pump-stock consists of a square wooden tube having the discharge-tube B on one side, and having also 30 lugs c c, between which the pump-handle D is pivoted. The inner end of the pump-handle d forms a segment of a spur gear-wheel, which intermeshes with a rack-bar, e, which is secured to the wooden pump-staff head f. 35 The pump-staff h is a metallic rod having the upper end flattened, and it is secured to the staff-head f by a bolt, i, the pump-staff passing longitudinally through the staff-head, so that it may be easily adjusted lengthwise 40 thereon. The width of staff-head f is such as to fit loosely between the sides of the upper section, A, of the pump-stock, and the back of the staff-head rests against a friction-roll, j, set in the back side of the pump-stock.

45 I is the coupling which closes the lower end of section A of the pump-stock and connects it with the lower section, which consists of an iron pipe, k.

Coupling I consists of a rectangular block 50 a little larger in diameter than the interior of section A, and having on its upper side a

flange, l, corresponding in outline to the interior of the pump-stock section A, but smaller in diameter. The edges of coupling-block I fit into a groove, m, formed around the inside 55 of section A, the said coupling-block being inserted in the grooves when the pieces forming the sides of tube A are put together, and an annular packing-ring, n, is arranged around the outside of flange l, filling tightly the 60 space between the flange and the interior of section A, thus making a water-tight joint. Within the space inclosed by flange l are two holes, o and p, extending through the coupling. Hole o is screw-threaded to receive the 65 lower section, k, of the pump-stock. Hole p is for the purpose of draining the upper section of the pump-stock to prevent freezing. It may be closed at the pleasure of the operator by means of a rod, r, extending along 70 the interior of the pump-stock, and having on its lower end a valve, s, and on its upper end a pin, t, which projects through a slot, u, in the side of the pump-stock. A plate, v, is mounted on a pin, t, on the outside, for the 75 purpose of covering the slot.

The pump-cylinder consists of a metallic tube, w, having its lower end closed by a rectangular base-plate, x, and its upper end closed by a cap-plate, y, which plates are connected by bolts z, thus clamping the tube w between them. Base-plate x is of peculiar construction. It has a central opening, 1, which extends only part way through the plate and is covered at the top by the check-valve 2. 80 From the lower end of opening 1 radial openings 3 extend to the sides of the base, and are covered at the outer ends with wire-cloth, the purpose being to prevent the entrance of sediment when the cylinder is set on the bottom 85 of the well.

The piston 4 is provided with a double check-valve, 5, and is rigidly secured to the pump-staff h, which passes upward through the pump-stock.

90 The operation is obvious.

The manner of connecting the pump-handle to the pump-staff gives ease and smoothness of movement, and the improved manner of connecting and draining the upper section 100 prevents the closing of the drain-outlet by freezing.

I claim as my invention—

In a pump, the combination, with the upper and lower sections of the pump-stock, of the above-described coupling-block, consisting of 5 a rectangular block adapted to fit into grooves in the walls of the upper section, and having the annular flange *l*, screw-threaded opening *o*,

and drainage-opening *p*, and the annular packing *n*, all arranged substantially as specified.

WILLIAM H. CLOUD.
